UNITED STATES PATENT OFFICE.

WILLIAM M. HOLLOWAY, OF AUSTIN, ILLINOIS, ASSIGNOR TO CHARLES W. SHONK COMPANY, OF CHICAGO, ILLINOIS, A CORPORATION OF NEW JERSEY.

COIN-ACTUATED MECHANISM.

1,131,628.

Specification of Letters Patent.

Patented Mar. 9, 1915.

Application filed May 19, 1911. Serial No. 628,169.

To all whom it may concern:

Be it known that I, WILLIAM M. HOLLOWAY, a citizen of the United States, residing in Austin, in the county of Cook and State 5 of Illinois, have invented a new and useful Improvement in Coin-Actuated Mechanism, of which the following is a specification.

My invention relates to improvements in coin actuated mechanism adapted for use in 10 money banks to register the amount of the deposit.

In this machine coins of different denominations may be received through the same slot and fall into a selecting device consisting of a pivoted carrier chute having an inclined side which positions the coins according to denomination, and which being oscillated on its pivot carries the coins flatwise past a series of lugs positioned to 15 counted each one, a coin of different denomination and which lugs actuate the registering device of a toy bank for registering the amount of money deposited in the bank. The oscillating coin carrier upon being 20 turned coincides with a gate or passage to discharge the coin from the carrier into the receiving chamber of the bank and when the register indicates the deposit of a certain amount, a projection upon the wheel of 25 higher denominations, operates a latch, and opens a door in the bottom of the casing to permit the withdrawal of the money from 30 the bank.

The invention consists in certain features 35 of novelty in the construction, combination and arrangement of parts all fully described with reference to the accompanying drawings and more particularly pointed out in the claims.

40 In the drawings Figure 1 is a front view of a toy bank containing this invention; Fig. 2 is a sectional view of the same on line 2—2 of Fig. 1; Fig. 3 is a vertical section on the line 3—3 of Fig. 5; Fig. 4 is a vertical section on the line 4—4 of Fig. 5; Fig. 5 is a front view similar to Fig. 1 showing the casing removed or in section; Fig. 6 is a view similar to Fig. 5 with some of the parts removed. Fig. 7 is a plan view of the mechanism removed from the casing; Fig. 8 is a horizontal section on the line 8—8 of Fig. 2; Fig. 9 is a vertical section on the line 9—9 of Fig. 8; Fig. 10 is a side elevation of one of the registering wheels showing the numerals

diagrammatically surrounding the wheel 55 and their arrangement.

In the drawings 11 is the coin carrier chute pivoted on the axis 12 and having the saw-tooth or double acting segment ratchet 13 engaged by the spring pawl 14, which 60 permits the carrier to be swung in either direction, but requires the movement of the carrier to be complete in one direction or the other before the pawl will permit its reversal. Attached to the carrier chute is the 65 operating handle 15 which projects through a slot 16 in the casing 17.

The chute or carrier 11 is provided with two plates 18, 19, placed parallel to each other and sufficiently near together so that 70 a coin of any denomination dropped into the chute will be held in an upright position. The construction is such that the coin is held flatwise, with its faces parallel to the axis of the carrier, and is sustained in position in 75 the chute according to its denomination by the stops 20, 21, 22, arranged in the chute to suit the diameter of the various coins. The sample illustrated is intended to accommodate the varying diameters of dimes, nickels 80 and quarters. The edge of the chute between the stops as at 23, 24, 25, is cut away to expose a segment of the coin lodged in the chute. The coin carrier chute has two spring connections 26, 27 with the frame of 85 the machine so that in whichever way the carrier chute may be moved by the handle 15, the springs will return it to the normal position indicated at Fig. 4. In this normal position the mouth of the coin carrier chute 90 is immediately beneath the coin slot 28 in the case of the machine. To protect the interior of the bank from being tampered with through the outer coin slot, and to prevent the dropping in of coins when the carrier 95 chute is not in normal position and ready to receive a coin, a guard plate 29 carried on the segment 30 pivoted to the axis 12, is held by the spring 31 connected to the framework of the machine at one of its ends and to the 100 trigger 32 at its other end. This trigger 32, when the coin carrier chute is in its normal position, bears against the projection 33, integral with the carrier chute, and thus holds the slots 34 of the guard plate 29 coincident with the mouth of the coin carrier chute. But when the coin carrier chute is moved forward by its handle 15 the upper 105

edge of the trigger 32 comes in contact with a projection 35 of the frame of the machine, which forces the trigger down and releases it from the projection 33, whereupon the 5 spring 31 retracts the guard plate to such position as to close and guard the outer coin slot in the casing of the machine. Said guard plate remains in this position until the coin carrier chute is returned to the limit 10 of its back movement whereupon the projection 33 on the carrier chute rides over and gets behind the trigger 32 and thus picks up the guard plate and uncovers the coin carrier chute in the latter's return to normal or open 15 position.

Axially coincident with the coin carrier chute, and preferably pivoted upon the same shaft 12, is the geared segment 36, meshing with the pinion 37, loose on the 20 shaft 38, for actuating the registering mechanism. This registering mechanism consists of two wheels, the cents wheel 39 and the dollar wheel 40 both loose on the shaft 38. Attached to the cents wheel 39 is a 25 double ratchet 41 connected by a spring pawl 42 with the pinion 37 in such manner that when the geared segment is moved forward or in the direction of the arrow the pinion 37 is caused to pick up the cents wheel and 30 move it through an arc corresponding to the arc through which the segment 36 has passed. A second pawl 43 from the frame of the machine engaging the double ratchet holds the gain thus made by the cents wheel 35 while the toothed segment 36 and pinion 37 are returning to their normal or starting position. Between the cents wheel and the dollar wheel are two gears, a mutilated gear 44 attached to the cents wheel and a complete gear 45 attached to the dollar wheel. 40 A mutilated pinion 46, having six teeth on one side and three on the other connects the two numeral wheels in such manner that when the wheel of the cents denomination 45 makes one complete revolution the motion is carried to the dollar wheel and the latter is moved forward one impulse.

Attached to the dollar wheel is the supplemental disk 47, to revolve therewith, and 50 carrying on its periphery the cam projections 48, 48. It will be noted that the cents numeral wheel is divided into twenty equal parts, each part representing five cents, one-twentieth of a dollar; and that the dollar 55 wheel is correspondingly divided into twenty parts. The cents wheel is marked as indicated in Fig. 10 with numerals from 5 to 00 while the dollar wheel is marked with two successive series of numerals from 60 each reading 1, 2, 3, 4, 5, 6, 7, 8, 9, 00, making it to register \$10.00 twice in a single revolution. In position to be acted upon by the cams 48 above mentioned, in the revolution of the registering wheels, is a pivoted 65 spring latch 49 engaging a hook 50 on the

hinged door 51, located in the bottom of the receiving chamber of the bank. It will be seen that for each \$10.00 registered the disk 47, in its revolution will, by one of the projecting cams 48, cause the spring latch 49 70 to be withdrawn, thus permitting the door 51 in the bottom of the bank to fall open by gravity and the contained coins to be discharged. After the door has been opened it may be closed and the hook 50 will snap 75 by the spring latch and become automatically locked thereto. Reverting now to the segmental gear: This gear is connected to the coin carrier chute and caused to move therewith only through the coin in said 80 chute by projections 52, 53, 54, arranged on the face of the segmental gear in such manner and in such angular relation that when a twenty-five cent piece is dropped into the chute its exposed face will engage one of 85 the projections whose angular relation is such that when the coin carrier is moved through its arc of movement it will move the geared segment far enough to advance the cents wheel through an arc indicating 90 twenty-five cents; and so in like manner with the dime and with the five cent piece. It will be noted that because of the flatwise presentation of the coins to the actuating projections on the gear segment it is possible 95 to insure great certainty of action and differentiation in the case of coins of different denomination, even though the sizes of the coins are not proportional to their respective values. This flatwise presentation 100 by offering a large surface for contact with the projections makes it possible to utilize projections of different lengths for different coins whose difference of value is not rotatable to their difference in diameter. The 105 flatwise presentation of the coins greatly simplifies their discharge from the coin carrier chute which is effected in the construction herein described through the lateral opening 55 normally covered by the spring 110 held gate 56. The outside edge of the coin carrier chute being at all times open, the coins are only held in by their contact with the frame plate 57. After a coin has been 115 deposited in the carrier chute, and said carrier chute has been moved through a complete down stroke, upon its return after passing the normal or open position and being carried to the termination of the return movement, said carrier chute will pick up 120 the gate 56 by contact with the projection 58 and push it out of the way, thus bringing the open side of the carrier chute coincident with the opening 55, whereupon the coin 125 will roll out into the deposit compartment 59 of the bank.

I claim:

1. In a mechanism for registering coins of different denominations, a graduated coin carrier chute for holding the coins in dif- 130

- ferent positions according to their size and in which the coins are held flatwise to the direction of movement of the chute, said chute being oscillatable about a horizontal 5 axis and its graduations being arranged to hold coins of different diameters at different distances from said axis, registering mechanism, and devices intermediate the registering mechanism and the coin carrier chute 10 engaged and directly operated by the coins in the chute when the latter is oscillated, substantially as specified.
2. In a mechanism for registering coins of different denominations the combination 15 of registering mechanism, a casing having a vertical partition therein provided with a coin discharge opening, and actuating devices therefor comprising a graduated, oscillatory coin carrier chute movable about a 20 horizontal axis and adapted to hold the coins flatwise to the direction of movement of the chute and its graduations being arranged to hold coins of different diameters at different distances from said axis, said 25 chute having one side thereof open adjacent to said vertical partition and adapted to discharge the coins through the discharge opening at the end of its forward movement, substantially as specified.
3. In a mechanism for registering coins of different denominations, a casing having a single deposit opening therein for all the different coins, a coin carrier chute oscillatable about a horizontal axis and adapted 30 to retain the coins flatwise to the direction of movement of the chute, register wheels, and a cogged segment having a projection located so as to be directly engaged by a coin 35
- positioned flatwise in said chute, said cogged segment operating the register wheels, substantially as specified. 40
4. In a multiple coin registering and adding bank having a single deposit opening for coins of varying denominations, the oscillatory coin carrier chute having an open side adjacent to a stationary frame plate containing a coin discharge opening, the coin being received and positioned flatwise to the direction of the motion of said carrier chute, in combination with a cogged 45 segment pivoted on the same axis as the carrier chute and having projections positioned to directly engage coins of different denominations held flatwise in the carrier, such projections having different angular 50 relations to impart movement to the cogged segment corresponding to the value of the coin engaged.
5. In a multiple coin registering and adding bank, having a single deposit opening 55 for coins of varying denominations and an oscillatory coin carrier chute, the combination of means for closing the deposit opening automatically by the movement of the coin carrier chute whereby the said deposit opening 60 is closed at all times except when in registry with the mouth of the coin carrier chute, said means consisting of a pivoted spring-held guard plate provided with a spring trigger for connecting it with the 65 carrier chute and disconnecting it therefrom by the movement of said carrier chute. 70
